(57) CLAIM

The ornamental design for a safety shield for a children's ladder, as shown and described.

DESCRIPTION

FIG. 1 is a front, right perspective view of a safety shield for a children's ladder in a configuration of use, showing our new design;

FIG. 2 is a front view thereof;

FIG. 3 is a rear view thereof;

FIG. 4 is a right side view thereof, the left side being a mirror image;

FIG. 5 is a front, left perspective view of the safety shield for a children's ladder, shown separately for ease of illustration;

FIG. 6 is a front view thereof;

FIG. 7 is a rear view thereof;

FIG. 8 is a right side view thereof, the left side view being a mirror image; and,

FIG. 9 is a top view thereof, the bottom view being a mirror image thereof.

The broken lines depict portions of the safety shield for a children's ladder that form no part of the claimed design. The broken lines showing a children's ladder in FIGS. 1-4, depict environmental structure that form no part of the claimed design.

1 Claim, 9 Drawing Sheets
